CASING FOR A STUDENT'S AVERAGE COMPUTER

Shirley McLarty, Dallas, Tex., assignor to
C. W. Adams, San Angelo, Tex.

Filed Aug. 21, 1963, Ser. No. 76,317

Term of patent 14 years

(Cl. D64—11)

FIG. 1

FIG. 2

FIG. 1 is a top plan view of a casing for a student's average computer showing my new design; and

FIG. 2 is a sided elevational view thereof.

The front, back and side portions not disclosed are plain and unornamented.

I claim:

The ornamental design for a casing for a student's average computer, as shown and described.
